STUFF GATE CONTROL

Albert Allen, Sharon, Mass., assignor to The Foxboro Company, Foxboro, Mass., a corporation of Massachusetts

Application November 26, 1937, Serial No. 176,417

4 Claims. (Cl. 137—139)

This invention relates to the control of a stuff gate of a paper-making machine, and in its more specific aspects, to apparatus for positioning the stuff gate from a remote station adjacent paper-weighing apparatus usually located at the dry end of the paper-making machine.

Generally speaking, the positioning of the stuff gate in the present practice of paper making is effected manually by an operator who by a turn wheel on the gate arbitrarily sets the gate to a position which he may deem proper following a determination of the weight of a sample of the paper coming from the dry end of the machine. Even though the paper weight may be off, an operator seldom resets the gate because of the effort involved in the back and forth travel between the distantly spaced stuff chest and the weighing machine, and the uncertainty of any adjustment the operator may make.

While certain attempts have been directed to devising automatic means for positioning the stuff gate in response to variations in certain properties of the paper affected by gate position, such as weight, density, and the like, such have not been entirely successful or practical, with the result that the industry still relies to a great extent on the unsatisfactory older practice of manually positioning the gate as above stated.

The present invention overcomes the disadvantages of the prior practices in providing a simple, practical and reliable apparatus for positioning and recording the position of a stuff gate, the apparatus embodying a control which may be operated from a remote station adjacent the weighing apparatus generally located at the dry end of the machine. The improved apparatus comprehends power means effective to open and/or close the gate, with the control functioning to so adjust the power means as to position the stuff gate at a desired setting, and to maintain this position, all as called for, for example, by the weight of the paper coming from the dry end of the paper-making apparatus. To this end a pneumatic system to actuate the gate is employed, the system utilizing a source of low-pressure air which may be the conventional mill air supply, and an air motor operatively related to the gate. Air from the source is supplied to the motor through a control head, with the control of the present system functioning responsive- 50 ly to its setting and to the position of the gate whereby to regulate the pressure supplied through said control head to the air motor.

More specifically, the control of the present invention utilizes an independent source of high-

pressure air, a pressure-regulating means preferably located at the remote control station adjacent weighing apparatus at the dry end of the machine, and a regulated pressure line therefrom to a control instrumentality incorporating first means frictionlessly responsive to the regulated pressure, second means movable in proportional correspondence to the gate, and third means correlating the first and second means with a control head so as to cause the air motor, through the control of pressure supplied thereto, to position the gate in proportional correspondence with the regulated pressure as set by the reducing valve aforesaid. By utilizing a regulating valve especially designed to hold the regulated pressure within extremely close limits regardless of variation in supply pressure, the gate is accurately positioned and its position maintained by the system of the present invention. Such a reducing valve is provided with adjusting means whereby different regulated pressures may be supplied to the control instrumentality, thus to provide for different gate positions as required.

The invention further provides for the recording of the regulated pressure delivered by the reducing valve. Such a record, due to the relation between the regulated pressure and the gate position, is by suitable translation a record of gate position. Thus, an operator at the control station remote from the position may set the reducing valve for a desired pressure and by observing the pressure record, is accurately advised of the gate position. This record is also useful to the machine operator as a guide to the operation of the machine. Thus, if repeated resetting is necessary, particularly in one direction, there is indicated the existence of an abnormal condition or change of condition in the general operation of the machine. Again, a record of the actual weight of the paper samples taken at convenient time intervals, together with the record of the stuff gate position, gives a valuable check on the general machine performance.

Other objects will be in part obvious and in part hereinafter pointed out in connection with the following analysis of this invention wherein is illustrated an embodiment of the invention in detail.

In the drawing:

Fig. 1 is a schematic diagram of stuff gate positioning apparatus and control therefor in accordance with the present invention; and,

Fig. 2 is a section through a pressure reducing valve forming a part of the control means illustrated in Fig. 1.

Referring to the drawing, wherein like reference characters denote like parts throughout the views, reference character 10 designates a head box having a discharge opening 11 for the flow of the pulp from the box to the web-forming apparatus, such arrangements being conventional and forming no part of the present invention. Flow of the pulp through the discharge opening 11 is controlled by a stuff gate 12 provided with a stem 13 which is adapted to be positioned by a gate-positioning element 14. In the construction illustrated, the upper end of the element 14 is provided with a turnbuckle 15 to which is connected the lower end of the stem 13, as by a pin 16, with the element 14 extending downwardly and axially of the stem and having its lower end operatively related to the diaphragm 17 of a pneumatic motor generally designated 18. With the gate biased to its closed position by a spring 19, the arrangements and connections are such that movement of the diaphragm in response to air pressure is transmitted to the positioning element 14, thence to the gate stem 13, and finally to the gate 12, thus to position the latter at various elevations across the discharge opening 11 of the flow box 10.

Pressure air is supplied to the motor 18 through an air line 22 connected through control head 21 with a supply line 20. The line 20 delivers to the interior of the control head 21 which is of the supply and waste type and which controls the pressure supplied to motor 18 through air line 22.

The control head 21 includes a double valve 23 carried by a stem 24 extending from diaphragm 25, the valve controlling communication between lines 20, 22, and also a vent to atmosphere. Air is supplied from line 20 through a suitable restriction 27a to the interior of the diaphragm and to a nozzle element 26 of a control couple (including a flapper 28). The flapper in covering and uncovering the nozzle varies back pressure in diaphragm 25 and the position of valve 23.

Considering now the mechanism of the present invention by which the control head supplies such pressure to the motor as is necessary to insure the desired gate position, the stem positioning element 14 carries a collar 30 against which engages an arm 31 of a bell crank adapted to turn bodily on the fixed axis of its cross arm 32, to the other arm 33, which may be adjustable in length, engaging against and positioning one end of a control lever 34. A spring 35 operative between a fixed abutment and an intermediate point of the lever 34 functions to yieldingly hold the lever 34 against bell crank arm 33 and arm 31 against collar 30.

Lever 34 forms one end of a bell crank which includes an offset cross link 45. The bell crank is suitably pivotally supported in spaced ears 44 of a movable plate 43 suspended between a bellows 40 and an opposing spring 42. Regulated air pressure is delivered to the bellows through an air line 41, and this pressure tends to distend the bellows against the bias of the spring 42 and so frictionlessly positions the plate 43 in correspondence with the pressure in the line 41.

The bell crank has a second arm 46, the angular relationship of which with respect to arm 34 may be adjusted by means of screw 47 operative between the cross link 45 and the arm 46. The arm 46 terminates in an in-struck tongue 48 against which the flapper 28 is spring-pressed.

With this construction the pivoted end of lever arm 34 is frictionlessly positioned responsively to the controlled pressure in line 41.

The lever 34 functions to correlate the action of the collar responsive to gate position with the means responsive to the regulated pressure according to a predetermined relationship. Thus, a particular pressure in the bellows 40 moves the fulcrum end of lever 34 to a particular position in correspondence therewith. Once this position is established, the lever through the action of its associated arm 46 on flapper 28 of the control couple, causes the control couple to so operate valve 23 that air is supplied to motor 18 at whatever pressure may be necessary to move the motor and gate 12 until its position, as measured by the bell crank arm 31, is in correspondence with the position of the fulcrum end of the lever 34 as determined by bellows 40. So long as the particular pressure is maintained in the bellows, the control operating as described functions to maintain the gate position so established.

Considering now the means for supplying regulated pressures to the bellows 40, whereby gate 12 may be positioned in proportional correspondence therewith, reference is had to Figs. 1 and 2, wherein a regulating valve 50 connected into the air line 41 is shown as arranged on a control panel 51, which is preferably located at a control station remote from the gate and preferably adjacent the weighing apparatus generally located at or near the dry end of the machine. This location of the control station is desirable, as a sample of the web coming from the dry end of the machine can be weighed, and the control apparatus operated from this point to make such adjustments in the gate position as the weighed sample would indicate to be necessary.

In considering the regulating valve, reference is made to the fact that it is specially designed for "dead end" service as represented by the line 41 and bellows 40, from which no air is bled as would necessitate a continuous or substantially continuous supply of air through the regulating valve to the dead end of the line. It is desirable too that the regulated pressure be held within close limits, regardless of variations in supply pressure.

To satisfy these requirements of dead end service, the regulating valve shown may be used. Referring to Fig. 2, a valve body is generally indicated at 52, having an inlet 53 into which is connected the air line 54 from a source of high pressure supply, and an outlet 55 into which is connected the air line 41 ending at bellows 40. Air from the high pressure line 54 passes into the chamber 56 in the valve body through a communicating passage 57. This passage is under the control of a valve 58 biased to a closing position on a seat member 60 by a spring 61. Valve 58 has a stem assembly 63 extending axially of and through the passage 57. Adjacent the upper end of the stem assembly is a valve 64 operatively related to a seat member 65 having a through air passage 66.

Seat member 65 is carried by a diaphragm 67 secured between the body 52 and a bonnet member 68 arranged on the valve body. A diaphragm 65 plate 70 serves to secure the seat member to the diaphragm and also forms a seat for an adjusting spring 71 adapted to exert pressure on diaphragm 67. The other end of the spring 71 reacts against a head carried by an adjusting screw 72 having a knurled operating knob 73.

Valve 64 is arranged in controlling relation to the passage 66 of the seat member 65, through which passage air from chamber 56 may pass to the interior of bonnet 68 and thence to at-

mosphere through a vent opening 14 in the bonnet wall.

The pressure in line 41 and in the bellows 40 is maintained corresponding to the pressure exerted by the adjusting spring 71 on the diaphragm 67 and the regulator in general may be regarded as effecting the desired static pressure on the bellows 40. The spring is adjusted to the desired pressure by operation of the stem 72 and knob 73. The pressure of spring 71 is opposed by the air pressure in chamber 56 and by the spring 61 tending to seat valve 58, and operates to adjust the air pressure in the chamber 56 until it is just sufficient to oppose spring 71 and move the valve stem assembly to a position in which both valve 58 and 64 are seated on their respective valve seats. Thus, changes in the upstream or high pressure do not affect the downstream or low pressure in the line 41 and bellows 40. If the downstream pressure tends to change due to leakage or to temperature, this pressure change operates diaphragm 67 and the two valves 58, 64 to bring back the downstream pressure to that corresponding to the pressure on the spring 71.

From the above it will be seen that the pressure in the dead end or downstream side of the line is maintained at a substantially constant value as determined by the setting of the adjusting spring 71, regardless of fluctuations of the supply pressure. The arrangement is further such that an increase of the compression of spring 71 increases the dead end pressure, and a compression of spring 71 decreases the dead end pressure, and a pressure. Thus, variations in the downstream pressure are delivered to the

bellows 40 through line 41, it follows that a record of this regulated pressure by suitable calibration constitutes a record of gate position. To provide such a record, a connection 80 from the line 41 to a recording instrument 81 is made, the recording instrument being preferably mounted on the control panel 51 and including a pressure-actuated pen recorder 82 by which a running record of the pressures in line 41 is made, thus to give a record of gate positions.

While a motor is shown for actuating and positioning the gate 12, under certain conditions as, for example, on failure of air, it may be necessary to actuate and position the gate manually. To this end the connection between the gate stem 13 and the positioning member 14 is made separable. By removing pin 16 the positioning member may be lowered, whereupon a hand wheel 95 threaded on the stem until it engages a fixed bracket or yoke member 96 through which the stem extends. Manipulation of the hand wheel in either direction thereupon actuates the gate 12 in opening or closing direction. This arrangement provides a simple means of converting from power to manual actuation and positioning of the gate 12.

As many changes could be made in carrying

out the above constructions without departing from the scope of the invention, it is intended that all matter contained in the above description or shown in the accompanying drawing shall be interpreted as illustrative and not in a limiting sense.

I claim:

1. In combination with a stuff gate, a fluid pressure motor for actuating the gate, a fluid supply line to the motor, control means for controlling the supply of fluid to said motor including first means frictionlessly responsive to a remote manual adjustment, second means responsive to gate position, and means for translating the action of said first and second means into control effects whereby said motor positions the gate in correspondence to the adjustment of said frictionlessly responsive means.

2. In combination with a stuff gate, a fluid pressure motor for actuating the gate, a fluid supply line to the motor, a control head of the supply and waste type in the line, a control couple operatively related to the control head, and adjustable control means including first means frictionlessly responsive to the adjustment of the control means, second means responsive to gate position, and means for translating through the control couple the conjoint action of the first and second means to the control couple whereby the couple causes fluid to be supplied through the

member, a bellows having a free end, and means positionable frictionlessly in correspondence with the end of said bellows and also positionable in correspondence with the means responsive to the position of the member and a pressure regulating valve located at a point remote from said member for maintaining the fixed pressure in said bellows, said valve having manually adjustable means for setting the value of the pressure to be maintained.

4. In combination with a stuff gate, a pneumatic motor for actuating the gate, a pressure air line to the motor, and control mechanism for causing said motor to actuate the gate to and maintain it at a position in correspondence with a predetermined value of air pressure comprising a pneumatic bellows member, means for supplying pressure air thereto, means located at a remote control station for setting the value of the pressure in the bellows, means responsive to gate position, a member positionable in accordance with the value of pressure in the bellows and the action of the gate-position-responsive means, and means for translating the position of said member into control effects on the value of the air pressure supplied to the motor.

ALBERT ALLEN.
